UNITED STATES PATENT OFFICE

MICHAEL R. MANGAN, OF CHICAGO, ILLINOIS

WIRE-SPRING FABRIC OR THE LIKE

Application filed April 12, 1928. Serial No. 269,425.

My invention belongs to that general class of devices known as fabrics and relates more particularly to a wire spring fabric for beds and like places. The invention has among its 5 objects the production of a device of the kind described that is simple, durable, inexpensive, resilient, comfortable, efficient and satisfactory for use wherever found applicable. More particularly it has as an object the 10 production of a fabric of the kind described made up of a plurality of units or elements which may be easily and quickly assembled and when assembled will securely lock the parts in operative position. It has as a further 15 object the production of a fabric in which the top face thereof is substantially level or flush throughout the fabric. Many other objects and advantages of the construction herein shown and described will be obvious to 20 those skilled in the art from the disclosure herein given.

To this end my invention consists in the novel construction, arrangement and combination of parts herein shown and described, 25 and more particularly pointed out in the claims.

In the drawings, wherein like reference characters indicate like or corresponding parts:

30 Fig. 1 is a top plan view of a portion of a fabric embodying the invention;

Fig. 2 is an enlarged view of a portion of the same;

35 Fig. 3 is a sectional view taken substantially on line 3—3 of Fig. 2;

Fig. 4 is a sectional view taken substantially on line 4—4 of Fig. 2;

Fig. 5 is a sectional view taken substantially on line 5—5 of Fig. 2;

40 Fig. 6 is a sectional view taken substantially on line 6—6 of Fig. 2, Figs. 4 to 6, inclusive being on a further enlarged scale from that of Fig. 2.

45 Fig. 7 is a sectional view taken substantially on line 7—7 of Fig. 6;

Fig. 8 is a view similar to Fig. 7, illustrating a modified construction;

50 Fig. 9 is a sectional view taken substantially on line 9—9 of Fig. 8; and

Fig. 10 is a side elevation of a typical spring construction.

In the drawings, wherein I have illustrated the preferred embodiment of my invention, referring to Fig. 1, it may be mentioned that 55 only a portion of a bed spring is shown for purposes of illustration. In this figure 1—1, etc., appears substantially as a series of rings, but in the case of a bed spring these represent the ends of coiled springs, these usually being 60 made substantially as shown in Fig. 10, in a series of spiral coils gradually contracting toward the center and thence enlarging again so that the two ends really are spaced 65 rings connected by a spiral spring portion. It is not necessary, however, to describe this in detail. My improved fabric particularly 70 consists of a series of coil springs arranged within a suitable frame 6 at the top and bottom, the spring members being connected to 75 each other and to the frame. The present invention relates more particularly to the means for tying or locking the several coil springs to each other or to the frame. As 75 shown, the several coils are connected by coil 80 springs 2 and 3 of the desired size as to length and diameter and of such gauge of spring wire as to give the required tension. These springs are connected at the center by forcing one spring in between the coils of an adjacent 85 spring without threading one into the coils of the other. The coils of one spring are, of course, spread as most clearly shown in Figs. 3 and 4, in which the coils of the spring 2 are spread to receive the coils of the spring 3. 85 When so forced together, the coils of the spring 3 engage at the inner sides of the coils of spring 2, and the parts are maintained in engagement. They may be readily assembled 90 in this manner, and when so assembled will under ordinary usage remain in assembled relation. The end of each coil is connected to the adjacent spring 1.

Referring particularly to Figs. 2, 6 and 7, the ends of each of the springs 2 and 3 are 95 provided with hooks 4 adapted to engage or hook on to the adjacent spring 1. However, if they were merely hooked over the springs 1, there would be a tendency for the same to slip sideways on the spring or possibly be- 100

come unhooked. To retain them in place and prevent sliding, keepers 5 are provided. These are merely short coiled springs which are slipped over the spring 1 as shown, the 5 coils being spread between the ends (see Fig. 7). When so arranged on the spring 1, they grip or clamp tightly on the same. The ends 4 of the coils are each hooked through the loops of the spring 5, as most clearly shown 10 in Figs. 6 and 7, and then under the spring 1. Obviously, when the parts are so assembled, the ends 4 are locked on the springs 1 and prevented from accidental disengagement or from sliding, and at the same time the hooked 15 end 4 passing through the coils of the keepers prevents these from slipping or becoming disengaged. When these are assembled the parts are locked together so that each spring 1 is locked to certain adjacent springs through 20 various springs 2 and 3. It will be particularly noted in this construction that by so arranging the parts the top face of the spring, as well as the bottom face, preserves a substantially flat level surface. The fabric is 25 secured to the frame 6 by means of springs 7 which may hook over the adjacent springs 1 at one end and be secured thereto by the keepers 5 and at the opposite end 8 may hook over the frame part 6. However, in this instance 30 similar keepers may be employed if so desired.

In the form shown in Figs. 8 and 9, 11 represents the spring corresponding to the spring 1 and 12 a spring corresponding to springs 2 35 and 3. In this case, small spiral springs 13 instead of being slipped over the springs 1, are threaded on the same, and the ends 12' of the springs 2 and 3 are threaded through the springs 13. While this is a satisfactory construction, I generally prefer to construct the 40 same as shown in Figs. 6 and 7.

It will be noted that in the constructions described, not only is a flat or level surface secured, but that the several parts are locked 45 together in such a manner that they will not slip or slide relative each other, and the assembling may be done without the aid of tools or machinery. It is not necessary to twist or bend the wires when the fabric is 50 made up in order to securely lock them together. Various other advantages will appear to those skilled in the art and need not be enumerated herein.

Having thus described my invention, it is 55 obvious that various immaterial modifications may be made in the same without departing from the spirit of my invention; hence I do not wish to be understood as limiting myself to the exact form, construction, 60 arrangement and combination of parts herein shown and described or uses mentioned.

What I claim as new and desire to secure by Letters Patent is:

1. In a fabric of the kind described, a series of springs, a plurality of connecting

spring arranged between said first-mentioned springs, and means for securing the ends of said connecting springs to said first-mentioned springs consisting of a coiled keeper arranged on the first-mentioned spring and engaging the same intermediate the coils of the keeper, said connecting springs extending through the coils of said keepers and back around the first-mentioned spring. 70

2. In a fabric provided with a plurality of spring members and in combination, means for tying said springs together consisting of a connecting member extending between adjacent springs, and means for securing said connecting member to a spring consisting of coiled springs slipped on said first-mentioned spring member and retained thereon by engagement between its coils with the first-mentioned spring, said connecting member provided with a hooked end and threaded through said coil and engaging the first-mentioned spring. 75

3. In a device of the kind described and in combination, a ring member and a connecting member, said connecting member provided with a hooked end and overlying and underlying said ring member, and a keeper consisting of a coiled spring extending transversely of the ring and mounted thereon with the ring lying between adjacent coils of the 90 spring, the hooked end of said connecting member threaded through said coiled spring whereby the keeper and connecting member cooperate and each one locks the cooperating member on the ring. 95

4. In a fabric of the kind described and in combination, a plurality of rings and resilient means for securing said rings together comprising coil springs, said coil springs having a hook at each end engaging one of 100 said rings, and means for securing said coil springs to said rings comprising a pair of coils integrally connected to each other so as to be resiliently urged toward each other, said coils being arranged on said hooks and 105 engaging said rings therebetween.

In testimony whereof, I have hereunto signed my name.

MICHAEL R. MANGAN.
